NECKTIE

Samuel Klaus, 1315 46th St.,
Brooklyn, N.Y. 11219

Filed Sept. 20, 1966, Ser. No. 3,933

Term of patent 3½ years

(Cl. D2—351)

FIG. 2

FIG. 1 is a front elevational view of a necktie showing my new design, portions of the necktie being broken away for convenience of illustration; and

FIG. 2 is an edge elevational view thereof.

The dominant feature of my design resides in the buttoned down strip on the front of the larger end of the necktie, all as shown.

I claim:

The ornamental design for a necktie, as shown and described.
